Primary Examiner — Holly Baynham*Assistant Examiner* — Rhea Shields(74) *Attorney, Agent, or Firm* — Winthrop & Weinstine, P.A.(57) **CLAIM**

The ornamental design for an air pulsating generator, as shown and described.

DESCRIPTION

FIG. 1 is a top perspective view of an air pulsating generator showing our design;

FIG. 2 is a bottom perspective view thereof;

FIG. 3 is a front elevational view thereof;

FIG. 4 is a back elevational view thereof;

FIG. 5 is a top plan view thereof;

FIG. 6 is a side elevational view of the right side thereof;

FIG. 7 is a bottom plan view thereof; and,

FIG. 8 is a side elevational view of the left side thereof.
